UNITED STATES PATENT OFFICE.

JOSEPH N. KELLY, OF SPRINGFIELD, OHIO.

CLAMP AND DIE FOR PUNCHES.

SPECIFICATION forming part of Letters Patent No. 390,863, dated October 9, 1888.

Application filed August 23, 1888. Serial No. 283,581. (No model.)

To all whom it may concern:

Be it known that I, JOSEPH N. KELLY, a citizen of the United States, residing at Springfield, in the county of Clark and State of Ohio, have invented certain new and useful Improvements in Clamps and Dies for Punches, of which the following is a specification.

My invention relates to improvements in dies and clamps for punches.

10 The object of my invention is to provide a combined clamp and die particularly adapted for holding round metal during the operation of punching the same, means being provided for guiding the punch accurately to the point 15 at which the opening is to be made thereby, the constructions being also adapted in a modified form to be used for clamping and holding flat or other shaped metal for punching.

My invention consists in the various constructions and combinations of parts herein-after described, and set forth in the claims.

In the accompanying drawings, which form a part of this specification, Figure 1 is a perspective view of a die and clamp embodying 25 my invention, the punch-stock being shown therein. Fig. 2 is a vertical sectional elevation view of the same with the drill-stock removed. Fig. 3 is a side elevation view of the clamping-jaws and dies and the sustaining-nut 30 in detail. Fig. 4 is a detail view of a punch-stock and punch, certain parts being shown in section. Fig. 5 is a detail sectional elevation view of a clamp and die in a modified form as adapted to punching flat metal.

35 Like parts are indicated by similar letters of reference throughout the several views.

In the said drawings, A represents an outer casing or shell, preferably cylindrical in form and provided on either side with circular openings A' A², diametrically opposite each other. Located within the outer casing, A, are the clamping-jaws B B', each provided with a semicircular notch or groove, a a', adapted, when closed together, to form an opening which 45 stands opposite and forms a continuation of the openings A' A² in the outer casing. The lower jaw, B', when in position, stands flush with the bottom of the casing A, and is preferably secured in this position by a small set-screw, b. The upper jaw, B, fits loosely in the 50 said casing, and is adapted to be raised vertically therein, a spline-key, b', being used to

prevent the same from turning. The upper part of the casing A is turned down to form a neck, A³, which is screw-threaded to receive a 55 cap, C, correspondingly internally screw-threaded to fit on said neck. The cap C is provided at the upper end with an opening, C', in which is placed a bushing, C². Immediately under the bushing C² is a chamber, C³, 60 one side of which is cut away, forming a semi-circular opening, C⁵.

The upper part of the upper jaw, B, is turned down to form a neck, B², the upper portion of which is screw-threaded to receive a nut, B³. 65 The neck B² projects into the cap C, which is turned out to receive the same, after which the nut B³ is screwed onto the said neck, thus firmly connecting the upper jaw and cap, while at the same time the cap is permitted to turn 70 in relation to said jaw. A handle, D, provided with a circular collar, D', fits over the cap C and is held thereon by a set-screw, e. The outer casing, A, is preferably adapted to fit in a base-piece, E, which is bored out to 75 receive the same, a set-screw, e', being provided to hold said casing in position. The base-piece E is adapted to be supported on the punch-table and secured thereto in the ordinary manner. The punch proper, d, fits in a 80 stock, F, which is provided at its lower end with a collar, f, and a clamping-ring, f', adapted to fit accurately in the bushing C² in the top of the cap C. The clamping-ring f' screws onto the stock F and in contact with a bushing, f², through which the punch d is inserted. The punch d, after being inserted in the bushing f², is forced into position in the stock F by screwing the clamping-ring f', the bushing f² being preferably tapered on its outside 85 and adapted to fit in a tapered seat in said stock, so as to insure the punch to be properly centered in its proper place. The punch d is provided at the upper end with a small head, which fits into a corresponding recess, f³, in the bushing f². In order to bring the strain centrally on the top of the punch d, and to prevent the head d' from being broken by the pressure thereon, the punch is rounded at its upper end, as shown at d' in Fig. 4. 900

The operation of the device is as follows: The punch d having been inserted in the stock F, as described, and the stock secured to the moving plunger of the punch in the ordinary

manner, the clamping device and die are set on the table of the punch in such a position that the punch and stock enter the clamp and cap, respectively. This insures the clamp and die 5 to be centrally located on the punch-table and in relation to the punching-plunger without any other adjustment. The base E is then fastened securely to the punch-table and the device is ready for use. The rods or bars to be 10 punched are inserted through the openings A' and A² of the casing A and between the jaws B B'. A turn of the handle D forces the said jaws tightly against said bar. The punch is then thrown into gear and descends through 15 the opening C in the upper cap, B, the punching or chip being discharged through an opening, c', in the lower clamp, B'. It will be seen that by this construction the work is held firmly in place during the operation of punching. The punch and stock is carried accurately to the point where the punching is to occur. It is also supported firmly against lateral movement, thus preventing breakage of 20 the punch and permitting the use of a small 25 punch through heavy material.

By reason of the chamber C³ and the opening C⁵ therein, in the event that a punch becomes broken the piece which is broken from the same, owing to the pressure thereon, will 30 be forced into the chamber C, and, following the curved walls of the same, will be discharged through the opening C⁵, thus preventing a further breakage of the punch or stock.

It is obvious that the same device in a modified form may be used for punching other 35 metals than round. In Fig. 5 a clamp and die adapted for punching flat metal are shown. The outer casing, A, in this form is substituted by a curved support, G, and the grooves a a' 40 and the openings A' and A² may be dispensed with, the clamps B B' being otherwise substantially the same.

Having thus described my invention, I claim—

45 1. In a clamp and die for punches, the upper and lower jaws, as described, one of which

is adapted to form a die and the other a guide for the punch, a screw-threaded cap attached to the upper jaw, and means for turning the same to raise and lower said jaw, substantially 50 as specified.

2. The combination, with the outer casing, of the upper and lower jaws adapted to form, respectively, a guide and die, as described, a screw-threaded cap attached to the upper jaw 55 and provided at the top with a bushing to receive the punch-stock, and an open chamber under said bushing, substantially as specified.

3. The combination of the upper and lower jaws adapted to form, respectively, a guide 60 and die, as described, a screw-threaded cap adapted to move said upper jaw, a handle attached to said screw-threaded cap, a bushing in the upper part of said cap, a punch-stock adapted to fit said bushing, and a punch provided with a rounded head secured in said punch-stock and adapted to fit in the opening 65 in the upper jaw, substantially as specified.

4. The combination, with the outer casing having the diametrically opposite openings 70 therein, of the upper and lower jaws having grooves which extend opposite to said openings, a screw-threaded cap on the top of said casing connected to said upper jaw, as described, so that a revolving movement of said 75 cap will produce a vertical movement of said upper jaw, and a handle adapted to turn said cap, substantially as specified.

5. The combination, with a clamp and die, as described, having the upper cap with a 80 bushing therein, and an open chamber under said bushing, of a punch-stock having a clamping-ring and bushing in the end thereof, and a punch with a rounded head adapted to fit in the said punch-stock, substantially as and for 85 the purpose set forth.

In testimony whereof I have hereunto set my hand this 20th day of August, A. D. 1888.

JOSEPH N. KELLY.
